Feeder for Printing Press

No 21859

Patented Oct. 19, 1858.

UNITED STATES PATENT OFFICE.

LEMUEL T. WELLS, OF CINCINNATI, OHIO.

PAPER-FEEDER FOR PRINTING-PRESSES.

Specification of Letters Patent No. 21,859, dated October 19, 1858.

To all whom it may concern:

Be it known that I, LEMUEL T. WELLS, of the city of Cincinnati, Hamilton county, State of Ohio, have invented a new and Improved Mode of Feeding Paper to Cylinder Printing-Machines, and I do hereby declare that the following is a full and exact description thereof, reference being had to the accompanying drawings and to the letters 10 of reference marked thereon.

This invention consists in mounting the nippers on a frame having a limited motion concentric with but independently of the cylinder, the object being to insure a more 15 perfect feed by causing the nippers to seize the paper while in a quiescent state or moving in an opposite direction to the cylinder.

In the accompanying drawings, Figure 1 is a transverse section of the cylinder and 20 accessories of a machine embodying my improvements, Fig. 2 is an end elevation and Fig. 3 a longitudinal or axial section of the same. Figs. 4 to 8 inclusive are views illustrating the construction of the cams and cam 25 rod.

1, is the cylinder, the shaft 2, of which is journaled in standards S, to one of which is attached a stationary spur wheel 3.

4 is a cog wheel gearing into the spur 30 wheel 3, 5 its shaft which is journaled within the cylinder 1 and is mounted with a cam 7².

A, A, is a vibrating frame loosely journaled on the shaft 2, of the cylinder so as 35 to be capable of moving independently of the latter.

10, 10, are the nippers attached to a shaft 11, which is journaled in the end of the frame A.

40 a' is a flat bar against which the nippers impinge in taking hold of the paper. The exterior surface of the bar a', is flush with the periphery of the cylinder.

The shaft 11, on which the nippers vibrate 45 is mounted at one end with a segmental pinion 11¹, which meshes into a corresponding one 9, of larger size which is also pivoted to the frame A.

50 p, is a stud projecting from the pinion 9, near its periphery and engaging as hereafter explained with a trip cam 6, attached to the cylinder.

t, is a friction roller on the frame A, forming the bearing of the cam 7².

55 u is a spring which when the pinion 9, is

released by the trip cam 6, rotates it so as to throw the nippers back into the position seen in Fig. 1.

v, is a spring which retracts the frame A, when released by the cam 7². 60

The operation is as follows: The cylinder being set in motion in the direction indicated by the arrow, the stationary wheel 3 causes the wheel 4, to revolve, and with it the cam 7², which by acting upon the friction roller t, impels the frame A, somewhat in advance of the motion of the cylinder, until the stud p, on the pinion 9, passing beyond the influence of the cam 6, the pinion 9, is rapidly rotated by means of the 65 spring u, in such way as to open the nippers or throw them completely back. This position is shown in Fig. 1, where the cam 7², has impelled the frame A, to its farthest limit. As the cam 7² continues to rotate its depressed portion allows the spring v, to retract the frame, which is thus drawn suddenly back until arrested by a stop k. At the same time the stud p, passing under the trip cam 6, rotates the nipper shaft 70 thereby closing the nippers tightly down upon the bar a', at the instant they are in position to seize the edge of the paper, and the frame A with its appendage is then carried forward with the cylinder in its rotation. This position of the parts is exhibited in Fig. 2. 75

The spring v, may be entirely dispensed with by employing a grooved cam 7, of the form indicated. A yoke 8 attached at one 80 end to the frame A, and at the other confined in the groove of the cam 7, serves in this case to draw the frame against the stop k, the various parts operating as previously explained. The frame A, may if preferred 85 move in grooves concentric with the cylinder.

Having thus fully described my invention, the following is what I claim as new therein and desire to secure by Letters Patent:— 100

In the described connection with the cylinder of a printing press I claim the vibrating frame A, bearing the nippers 10, and opposing bar a', and operated substantially in the manner and for the purpose set forth. 105

August 14th, 1858.

LEMUEL T. WELLS. [L.S.]
